UNITED STATES PATENT OFFICE.

LOESER KALINA, OF NEW YORK, N. Y.

GARMENT-HANGER.

1,049,867.

Specification of Letters Patent. Patented Jan. 7, 1913.

Application filed June 19, 1912. Serial No. 704,596.

To all whom it may concern:

Be it known that I, LOESER KALINA, a citizen of the United States, and a resident of the city of New York, borough of Brooklyn, in the county of Kings and State of New York, have invented a new and Improved Garment-Hanger, of which the following is a full, clear, and exact description.

The object of the invention is to provide 10 a new and improved garment hanger for supporting coats, vests, suits, trousers, skirts, shirt waists and other garments, and adapted to be folded into a comparatively small space for convenient carrying in a vest 15 pocket or stowing it away in a traveling bag or other similar traveling article. For the purpose mentioned use is made of a support for suspending the garment hanger from a hook or the like and for receiving 20 side arms made in foldable sections, the support being made in two parts, of which one forms a casing open at the sides for the side arms to pass into, and a cover for covering the open sides and for forming an extension 25 of the casing to suspend the support from a hook or the like.

A practical embodiment of the invention is represented in the accompanying drawings forming a part of this specification, 30 in which similar characters of reference indicate corresponding parts in all the views.

Figure 1 is a side elevation of the garment hanger with the side arms extended and in the form of telescoping sections; Fig. 35 2 is a sectional side elevation of the same with the parts in folded position; Fig. 3 is a similar view of the same partly extended; Fig. 4 is an edge view of the same; Fig. 5 is a sectional plan view of the same on 40 the line 5—5 of Fig. 2; Fig. 6 is a perspective view of the garment hanger in folded position; Fig. 7 is a side elevation of the garment hanger with the side arms extended and in the form of links; Fig. 8 is an edge 45 view of the same with the links in folded position; Fig. 9 is an enlarged sectional side elevation of the casing and parts of the innermost links; Fig. 10 is a side elevation of some of the links with the 50 outermost one in folded position; Fig. 11 is a plan view of the links of one side arm; and Fig. 12 is an enlarged sectional side elevation of the lower end of the casing.

The garment hanger illustrated in Figs. 55 1 to 6 consists essentially of a casing A,

arms B, B' each made in telescoping sections B², B³, B⁴ and B⁵ and adapted to be folded within the casing A and confined therein by a cover C, as hereinafter more fully described, the cover C also serving as 60 an extension of the casing A for supporting the casing from a hook, nail or the like. The innermost sections B², of the side arms B and B' are connected by pivots D with the casing A at the lower end thereof so that 65 when the sections B⁵, B⁴, B³ and B² are telescoped they may be swung upwardly into the casing A, as plainly indicated in Figs. 2 and 3. The outer ends of the outermost sections B⁵ are provided with rings E 70 connected with links F having their terminals connected with each other by a chain, cord, cable or other flexible connection G, so that when the side arms B, B' are telescoped and in folded position within 75 the casing A then the said links F also extend within the casing and likewise the flexible connection G, which latter is folded onto the pivotal ends of the innermost telescoping sections B², as plainly indicated in 80 Fig. 2. The casing A is open at the sides for the telescoping side arms B, B' to pass into the casing and the upper end A' of the casing is provided with a swivel H having a transversely-extending bearing H' engaged by a pivot H² held on the free ends of the side arms of the cover C, which latter is preferably made U shape to form a hook when extended for hooking the cover onto a hook, nail or other suitable support. 85 By having the swivel H, the cover C and the casing A can be turned one relative to the other into any desired position, and the cover C can also be swung into such position over the casing A so that its side arms 90 pass over the openings at the sides of the casing A to close the same and thus confine the folded side arms, the links F and the flexible connection G within the said casing. It is understood that when the cover C is 95 swung up into extended position it is necessary to give a quarter turn to the cover (see Fig. 1), so as to permit of hooking the cover onto a nail in a wall or other support to allow extending of the side arms approximately parallel with the wall for properly supporting garments. It is understood that when the hanger is extended and suspended as described, the casing A with the extended 100 arms and the garment hung thereon can be 105 110

readily turned on the swivel H until the desired position is obtained according to the surrounding space. This result is attained by connecting the casing A and cover C 5 with each other by the swivel H. It will be noticed that the middle portion of the cover C when the latter is swung into closed position closes the lower or open end of the casing A so as to hold the flexible connection G within the casing. The lower end of the casing A is open for the passage of the flexible connection G into or out of the casing and the lower end of the casing is provided with stop plates A² for the innermost links B² to rest on when in extended position. The head H² of the swivel H extends within the casing A and is in the form of diametrical arms extending inwardly between the terminals of the folded sections 10 B⁵ of the side arms B, B' (see Fig. 2) at the time the cover C is in closed position. Now when the cover C is swung upward into open position and given a quarter turn (see Fig. 3) then the swivel head H² acts on the 15 free upper ends of the outermost sections B⁵ of the folded side arms and swings the latter outward in opposite directions, thus starting the side arms and allowing the same to swing downward by their own gravity until the sections B² rest on the stops A². The sections B³, B⁴ and B⁵ are mounted to slide loosely in their containing sections B², B³ and B⁴ so that the sections B³, B⁴ and B⁵ now readily slide outward into 20 extended position either by their own gravity or by the operator pulling on the outer ends of the sections B⁵.

From the foregoing it will be seen that by the arrangement described the cover C 40 serves to close the casing A whenever it is desired to confine the folded side arms B, B', links F and the flexible connection G therein, and when the garment hanger is in use and the cover C is in open position it 45 forms an extension of the casing A to support the garment hanger from a hook or other suitable support. It will further be noticed that when the parts are in folded position and the cover C is closed then the 50 garment hanger takes up very little room, approximately that of an ordinary pocket knife, and hence can conveniently be carried in the vest pocket or stowed away in a traveling bag or other similar article.

55 It is understood that when the garment hanger is in use, a coat, vest, shirt waist or the like can be readily hung on the side arms B, B', while trousers, skirts and other garments can be hung onto the flexible connection G.

In the form shown in Figs. 7 to 12, the side arms B and B' are each made in the form of a series of links I, I', I², I³ and I⁴, pivotally connected with each other and 60 with the innermost links I fulcrumed on a

pivot D' held in the lower end of the casing A provided with a cover C of the same construction as above described in reference to the garment hanger having side arms made in telescoping sections. The links I, I', I² 70 and I³ are provided with stop lugs I⁶ adapted to be engaged by shoulders I⁷ formed on the links I⁷, I², I³ and I⁴ so as to hold the said links in extended position and slightly in the form of an arch, as indicated in Fig. 75 7. The stop lugs I⁶ are also adapted to be engaged by shoulders I⁷ on the links I⁴, I³, I² and I' to hold the said links against dropping downward when in folded position, as will be readily understood by reference to Fig. 10, which shows the outermost link I⁴ in folded position on the next link I³. The innermost links I and I' are provided at their fulcrum ends with shoulders I⁸ adapted to rest on transverse pins J secured to the casing A at the lower end thereof, and over the pins D' and J extends a retaining plate K provided with a central notch K' (see Figs. 8 and 12) for the inner or pivotal ends of the lugs I to rest on so as 80 to hold the same against lateral movement on the pivot pin D'. In using this garment hanger the links forming the side arms B, B' can be readily swung outward into extended position at the time the cover C is in 85 open or uppermost position and when the parts are extended the garment hanger can be readily hung upon a hook, nail or other support by engaging the cover C with it, and the garment can be readily placed in 90 position over the extended side arms B and B'. When it is desired to fold the garment hanger, the links I⁴, I³, I², I' and I are 95 successively folded one upon the other and finally swung into the casing A, after which 100 the cover C is swung downward so as to close the open sides of the casing A thereby confining the folded links of the side arms B and B' within the casing A.

Having thus described my invention, I 110 claim as new and desire to secure by Letters Patent:

1. A garment hanger, comprising side arms made in foldable sections, a casing adapted to hold the said arms in extended 115 or folded position, a cover, and a swivel and hinge connection connecting the said casing and cover, the latter being adapted to close the casing to confine the folded side arms therein, the said cover being also adapted to 120 form a hook extension of the casing to provide a support for the garment hanger.

2. A garment hanger, comprising side arms made in foldable sections, a casing in which the said arms are pivoted, a cover, 125 and a swivel and hinge connection connecting the casing and cover, the latter being adapted to close the casing or to form a supporting extension thereof.

3. A garment hanger, comprising a cas- 130

ing open at the sides, a cover approximately U shape, a swivel held on one end of the casing and provided with a bearing, a pivot on the said cover engaging the said bearing, 5 the sides of the said cover being adapted to pass over the sides of the said casing to close the same, and side arms attached to the said casing and adapted to be folded therein, the said cover when closed confining 10 the folded side arms in the casing.

4. A garment hanger, comprising a casing, side arms made in foldable sections and pivoted in the said casing, the side arms when in folded position being adapted to 15 be swung into the said casing, a supporting hook, and a swivel connecting the said supporting hook with the casing, the swivel having a head within the casing and the 20 said swivel head being in the form of diametrical arms extending between the free ends of the said folded side arms.

5. A garment hanger provided with a casing, side arms made in foldable sections and pivoted in the said casing, the side arms when in folded position being adapted 25 to be swung into the casing, a cover for the said casing to close the same and thereby confine the side arms in the casing, and a swivel connecting the casing with the cover, the swivel having a head in the form of 30 diametrical arms extending between the free ends of the said side arms to start the latter on turning the same.

In testimony whereof I have signed my name to this specification in the presence of 35 two subscribing witnesses.

LOESER KALINA.
